UNITED STATES PATENT OFFICE.

EUGENE FREDRICK AHLQUIST, OF MINNEAPOLIS, MINNESOTA, ASSIGNOR TO
SECURITY ENVELOPE COMPANY, OF SOUTH MINNEAPOLIS, MINNESOTA, A
CORPORATION OF MINNESOTA.

ENVELOPE.

Application filed November 21, 1921. Serial No. 516,727.

To all whom it may concern:

Be it known that I, EUGENE FREDRICK AHLQUIST, a citizen of the United States, resident of Minneapolis, county of Hennepin, State of Minnesota, have invented certain new and useful Improvements in Envelopes, of which the following is a specification.

This invention relates to new and useful improvements in envelopes particularly of the expansion type and it more specifically relates to such envelopes employing what is known in this art as gussets.

Such envelopes as at present constructed comprise a back member with which the flap or cover is integral and a front member while the gusset is substantially U-shaped and is secured along its marginal portions to the sides and bottom of the two members. Likewise, it is customary to secure a lining to the interior faces of the front and back members. In envelopes of such types, the front and back members are frequently torn away from the gusset. This more often occurs at the juncture of the gusset with the back member and particularly adjacent the upper end of the gusset.

The object of this invention therefore is to provide an improved envelope.

Other objects of the invention will more fully appear from the following description and the accompanying drawings and will be pointed out in the annexed claims.

In the drawings there has been disclosed a structure designed to carry out the objects of the invention, but it is to be understood that the invention is not confined to the exact features shown as various changes may be made within the scope of the claims which follow.

In the drawings:

Figure 1 is a perspective view of the improved envelope showing one form of tab reinforcement;

Figure 2 is a view in perspective of the gusset with a modified form of tabs;

Figure 3 is a perspective view of a five-piece envelope embodying the invention; and

Figure 4 is a detail view of a back corner of the envelope shown in Figure 3.

The envelope is here shown as comprising a back member 3 and a front member 4. The envelope cover or flap 5 is shown

as integral with the back member. The front and back members are joined along the marginal portions of their sides and bottom by means of a gusset 6.

The preferred form of gusset here shown is in bellows-like form and is therefore expandable. The gusset is formed with side marginal flanges 7 and bottom marginal flanges 8. The flanges 7 are adapted to be secured, as by the usual adhesive, to the side marginal portions of the front and back members while the flanges 8 are similarly secured to the bottom marginal portions of those two members.

In the selected embodiment of the invention here shown, a tab is provided on a marginal gusset flange which tab is adapted upon envelope assembly to be folded over the adjacent edge of an adjacent front or back member and secured to the face thereof. The tab is secured to the face of the member which is opposite to that to which the remainder of the tabbed gusset flange is secured.

The tab 9 is simply provided by making one cut in the terminal portion of a gusset flange 7 which cut preferably inwardly extends to the fold of the flange. Such tab 9, when the envelope is assembled with the gusset flange adherent to the inner marginal side and bottom portions of the front and back member, is folded over the edge of the members and is secured, as by an adhesive, to the adjacently presented portion of the outer face of the front or of the back member or both. In the present commercial form of this invention, a single such tab 9 is terminally formed on the two rear gusset flanges and each is folded over and secured to the adjacent outer faces of the back member. The front tabs are omitted in such form.

In Figure 2 is shown a modified tab form wherein two adjacent cuts are made inwardly from the edge to the fold of the marginal gusset flange 7 so as to produce an intermediate tab 10 which is adapted to be folded and secured to one of the members of the envelope. Similarly, if desired, such tabs may be formed in the marginal flanges 8 and likewise secured to the face of the front or back member opposite that to which the remainder of the gusset flange is secured.

While the use of this novel tab construction is advantageous in connection with the above-described three-piece expansion envelopes, it is more particularly adapted for 5 use with expansion envelopes of the five-piece type wherein front and back linings are employed. In such envelope, the adjacent marginal flanges 7 of the gusset are secured by an adhesive between the linings 10 and the adjacent front and back members. In such construction the reinforcing terminal tabs 9 are preferably employed and they are folded outwardly to embrace the edge of the back member. Thus the back is 15 prevented from separating from the inner lining adjacent the flap due to frequent opening and closing of the filled envelope. Such a five-piece envelope embodying this invention is shown in Figure 3 wherein the envelope is shown to consist of a back member 3 and integral flap 5. The outer faces of the adjacent side marginal flanges 7 and bottom marginal flanges 8 of the gusset 6 are secured by an adhesive to the inner faces 20 of the corresponding side and bottom marginal portions of the back member. The back inner lining 11 is secured by an adhesive to the inner faces of the flanges 7 and 8. The terminal tabs 9 of the back 25 flanges 7 of the gusset are outwardly extended and folded over and secured by an adhesive to the adjacent portion of the outer face of the back member 3. Preferably, in such construction, the tabs 9 are only used 30 at such back portion thus reinforcing the envelope at the two points of greatest strain and wear. The front member is secured by an adhesive along its sides and bottom to the outer faces of the side and bottom gusset 35 flanges 7 and 8, while the front inner lining 12 is similarly secured along its marginal portions to the inner faces of the marginal flanges 7 and 8 of the gusset. The reinforcing tab construction is not so necessary 40 at this front end as there is not present the frequent strain tending to separate the front member from the gusset and lining due to 45 the absence of the flap.

I claim as my invention:

50 1. An expansion envelope having front

and back members, a gusset to form the sides and bottom of the envelope, marginal flanges provided along both edges of the gusset whereby the gusset may be secured to the marginal portions of the front and back members and a tab provided on a marginal flange of the gusset and adapted to be folded over the edge of an adjacent member and secured to the face thereof whereby the envelope is strengthened. 55

2. An expansion envelope having front and back members, a gusset to form the sides and bottom of the envelope, and marginal flanges provided along both edges of the gusset whereby the gusset may be secured to the marginal portions of the front and back members, one of the marginal flanges of the gusset being cut to provide a tab adapted to be folded over the edge of an adjacent member and secured to the face 60 thereof whereby the envelope is strengthened. 65

3. An expansion envelope having front and back members, a gusset to form the sides and bottom of the envelope, and marginal flanges provided along both edges of the gusset whereby the gusset may be secured to the marginal portions of the front and back members, one of the marginal flanges of the gusset being cut adjacent its 70 terminus to provide a terminal tab adapted to be folded over the edge adjacent the member and secured to the face thereof whereby the envelope is strengthened. 75

4. An expansion envelope having front and back members, linings therefor, a gusset to form the sides and bottom of the envelope, and marginal flanges provided along both edges of the gusset whereby the gusset flanges may be secured between the front 80 member and its lining and between the back member and its lining, in combination with terminal tabs on said gusset flanges at the upper side of the envelope whereby said tabs may be outwardly and backwardly 85 folded and secured to the outer face of the back member. 90

In witness whereof, I have hereunto set my hand this 19th day of November, 1921.
EUGENE FREDRICK AHLQUIST.
